Adolph Geiss

United States Patent Office.

ADOLPH GEISS, OF BUFFALO, NEW YORK.

Letters Patent No. 100,999, dated March 22, 1870.

IMPROVEMENT IN RAILWAY-CAR COUPLINGS.

The Schedule referred to in these Letters Patent and making part of the same.

I, ADOLPH GEISS, of Buffalo, in the county of Erie and State of New York, have invented certain Improvements in Car-Couplings, of which the following is a specification.

The nature of my invention consists in providing a railroad car with a self-engaging coupling. I refer to the drawing which makes part of the following specification, and as illustrating my invention more fully.

Figure 1 represents my car-coupling in a perspective view.

Figure 2 is a longitudinal section of the coupling-head A, represented in fig. 1, except the coupling-link, which is bent, so as to answer for various heights of cars.

Letter A is the coupling-head. It is provided with a round shaft, A', which is to be surrounded by a spring of metal or rubber for the purpose of receiving the concussion of the moving cars. A is to be secured to a car in the usual way.

B B are two rubber plates within head A. They have for their object to act upon pinch-plates C C, in order to cause C C to pinch upon coupling-link D, the purpose of which will be explained hereafter.

C C are two metal plates. The same are jointed like a hinge, as plainly seen in fig. 2, and have for their object the holding of link D in such a position as to enable the self-coupling of the car.

D is the coupling-link.

E is the coupling-bolt.

F is the coupling-bolt bracket. It is for the purpose of holding the bolt E in a perpendicular position whenever the same is lifted out of the link D.

G is an angle-plate. It is provided with a tapering slot-hole, G'. It is secured to the head A by means of a set-screw, as plainly seen in fig. 1, and has for its object to uphold the bolt E when the same is lifted out of link D.

A small plate-spring, H, is acting at the end of

angle-plate G, in order to slide or push G out; the tapering slot-hole of plate G being of corresponding size with the bolt E, so it may impinge on said bolt E, in order to hold it up whenever it is lifted out until plate G be pushed back by coming in contact with an angle-plate G of the coupling-head A secured to another car.

It will be observed that as the springs H H are pushing plates G G of heads A A outward so as to project over the head A A, they will, when cars are shoved together, come in contact with each other before the heads A A will be brought together; hence G G will be pushed back and the bolt E released, so that it may drop into the head and through the coupling-link D.

It will also be observed that as the hinged plates C C pinch upon link D, whenever it is shoved into A, and is held there in a horizontal position, therefore if two cars are provided with this coupling, and one of the coupling-heads is provided with a link, D, secured between plates C C, the cars may be coupled together merely by moving cars together, as it does not require the assistance of a person to joint the link D in its proper place.

I am aware of the patent of W. Cottrell, October 5, 1869, but claim nothing thereof.

Having thus fully described my invention, What I claim as new and useful is—

The hinged plates C C, in combination with the springs or plates B B, the link D, the bolt E, angle-plate G, spring H, and bracket F, all constructed and arranged as described, and to operate substantially as set forth.

ADOLPH GEISS.
